OUTDOOR GROUND LEVEL LIGHTING FIXTURE

Hans Paul Ludwig Geisler, Norderstedt, Germany, assignor to Deutsche Texaco Aktiengesellschaft, Hamburg, West Germany

Filed Apr. 24, 1972, Ser. No. 247,253

Claims priority, application West Germany Jan. 12, 1972

Term of patent 14 years

Int. Cl. D26—03, 05

U.S. Cl. D48—31

FIG. 1 is a perspective view of an outdoor ground level lighting fixture showing my new design.

FIG. 2 is a side elevation view thereof.

The lighting fixture is shaded to indicate contrast.

I claim:

The ornamental design for an outdoor ground level lighting fixture, as shown and described.
